INVENTOR

UNITED STATES PATENT OFFICE.

HENRY JEPSON LATHAM, OF BROOKLYN, NEW YORK.

DESIGN FOR SIGN-LETTERS.

SPECIFICATION forming part of Design No. 20,855, dated June 23, 1891.

Application filed March 18, 1891. Serial No. 385,561. Term of patent 7 years.

To all whom it may concern:

Be it known that I, HENRY JEPSON LATHAM, a citizen of the United States, residing at Brooklyn, in the county of Kings and State of New York, have invented and produced a new and original Design for Sign-Letters, of which the following is a specification, reference being had to the accompanying drawings, forming part thereof.

Figure 1 represents a front view of the letter. Fig. 2 represents a side view of the same letter.

My invention consists in a design for sign-

letters which bear upon their outer surface spiral flutings, which give to the front thereof a rope-like appearance, the rear portion being flat, as shown in the illustration. The rear portion might be hollow, as shown in the model submitted.

What I claim is—

The design for sign-letters, as herein shown and described.

HENRY JEPSON LATHAM.
